UNITED STATES PATENT OFFICE.

NELSON W. DUFF, OF KANSAS CITY, MISSOURI.

FIRE BOX.

Application filed May 6, 1927. Serial No. 189,323.

My invention relates to improvements in fire boxes, particularly those employed for use in connection with steam boilers, and which employ hydro-carbon fuel.

5 One of the objects of my invention is to provide a novel fire box of the kind described, which is simple, cheap, durable, which is economical in the use of fuel, and which is efficient in its operation.

10 My invention provides further a novel baffle wall, which serves to effectively intermingle and diffuse the gaseous products of combustion, and which has means for holding back and guiding forwardly said gaseous products 15 delaying their discharge from the fire box, and thereby retaining therein the heat produced therefrom.

The novel features of my invention are hereinafter fully described and claimed.

20 In the accompanying drawings, which illustrate the preferred embodiment of my invention,

Fig. 1 is a side elevation, partly broken away, of a boiler of usual type, provided with 25 my improved fire box.

Fig. 2 is a horizontal section on the line 2—2 of Fig. 1.

Fig. 3 is a view partly in front elevation and partly in vertical section on the line 3—3 30 of Fig. 1.

Fig. 4 is a section on the line 4—4 of Fig. 2.

Similar reference characters designate similar parts in the different views.

1 designates a boiler of usual tubular stationary type having a front portion 2 disposed over a fire box 3, the latter being provided with an inner lining 4 along its side walls, which lining is preferably of refractory material, such as fire clay or brick.

40 In the fire box 3 is a transverse rear wall 5, which is preferably of refractory material, and which at its front side has a portion which inclines upwardly and forwardly, and is preferably concave.

45 In the fire box 3 forward of and spaced from the rear wall 5 and extending to the side walls 4, is a transverse perforate baffle wall 6, which is provided with forwardly and rearwardly extending passages 7.

50 In the fire box 3 forward of and spaced from the wall 6 is a wall of similar construction, designated by 8 and which is also provided with forwardly and rearwardly extending gas passages 7.

55 The front sides of the walls 6 and 8 have preferably the same form as the front side

of the rear wall 5. The concavely inclined portion 9 of each of the walls 5, 6 and 8, extends preferably downwardly and rearwardly from the top of the wall. It will be 60 noted that the concave arcuate front portion of each of the walls, 5, 6, and 8 extends forwardly and upwardly to a horizontal plane which is tangent to the arc. The effect produced by this construction is to cause 65 the gaseous products to travel upwardly and forwardly and thence, due to their momentum, downwardly and rearwardly, so as to effect a whirling movement around the center of the arc, thus materially delaying their 70 progress from the fire box.

For projecting the gaseous products of burning fuel against the front side of the front wall 8, any suitable means may be employed. In the drawings, I have shown for 75 this purpose two oil burners 10, which are respectively provided with fuel oil by means of two pipes 11, which extend through the front side of the fire box 3 and which are connected at their outer ends to a supply 80 pipe 12, which is connected to any suitable source of oil supply, not shown.

In the operation of my invention the gaseous products of combustion are projected rearwardly through the fire box against the 85 front side of the wall 8. A portion of the gaseous products is projected upwardly and forwardly, as is indicated by the arrows forward of said wall.

A portion of the gaseous products passes 90 through the openings 7 in the wall 8, and a part of the products so passing strikes the front side of the wall 6 and is upwardly and forwardly diverted, as indicated by the arrows adjacent to and at the front of the 95 wall 6.

Some of the gaseous products pass through the passages 7 in the wall 6 and strike the front side of the rear wall 5, which causes 100 said products to travel upwardly and forwardly as indicated by the arrows forward of and adjacent to the rear wall. Owing to the draft through the passages 7 of the walls 6 and 8, portions of the gaseous products which are given a whirling movement at the 105 front of said walls, as has been described, pass rearwardly through said passages, thus subjecting them to further heating by contact with the hot walls, and also delaying their progress through the fire box.

110 By means of such retardation and change of course of the gaseous products during

their passage from the front wall 8 through the fire box, a maximum amount of their heat is retained in the fire box and is conducted therefrom to the portion 2 of the 5 boiler which extends over and is spaced from the walls 5, 6 and 8. By this means a maximum amount of water in the boiler is heated with a minimum of fuel.

The gases, with air mingled therewith, 10 pass through the fire box and into and through the tubes 13, provided in the lower and rear portion of the boiler 1 and from thence through the usual rear space 14, in the boiler, into and through the tubes 15, which 15 extend in the usual manner into the forward extension 2 of the boiler and from thence to the atmosphere through the usual smoke stack 16.

I do not limit my invention to the structure shown and described, as many modifications, within the scope of the appended claim may be made without departing from the spirit of my invention. 20

What I claim is:

A fire box having a rear wall and a transverse wall forward of and spaced from the rear wall and having passages extending rearwardly therethrough, the upper front portion of said transverse wall having a concave arcuate portion extending upwardly 25 and forwardly to a horizontal plane that is tangent to the arc at its upper end. 30

In testimony whereof I have signed my name to this specification.

NELSON W. DUFF.
